Attorney

UNITED STATES PATENT OFFICE.

ARTHUR J. LARKIN, OF COUNCIL BLUFFS, IOWA, ASSIGNOR OF ONE-THIRD TO JOSEPH J. DODDS, OF OMAHA, NEBRASKA.

POWER WHEEL.

Application filed June 22, 1926. Serial No. 117,844.

This invention relates to a power wheel and it is an object of the invention to provide a device of this kind whereby pull may be effected upon a flexible member, such as 5 a cable, for pulling automobiles out of a ditch or the like and in connection with other operations requiring a pull or lift not in excess of five thousand pounds.

The invention consists in the details of 10 construction and in the combination and arrangement of the several parts of my improved power wheel whereby certain important advantages are attained and the device rendered simpler, less expensive and 15 otherwise more convenient and advantageous for use, as will be hereinafter more fully set forth.

The novel features of my invention will 20 hereinafter be definitely claimed.

In order that my invention may be the 25 better understood, I will now proceed to describe the same with reference to the accompanying drawing, wherein:—

Figure 1 is a view in top plan illustrating 30 a power wheel constructed in accordance with an embodiment of my invention;

Figure 2 is a sectional view taken substantially on the line 2—2 of Figure 1;

Figure 3 is a detailed sectional view taken 35 substantially on the line 3—3 of Figure 2;

Figure 4 is a fragmentary view in edge elevation of a portion of the wheel as herein disclosed.

As disclosed in the accompanying drawing, 40 1 denotes an axle or drum of requisite dimensions and which has fixed to its extremities the wheels 2 of relatively large but equal radii. These wheels 2 are spaced apart one with respect to the other and each of said 45 wheels at its peripheral portion is provided with a series of laterally disposed and outstanding projections 3. These projections or fingers are preferably equidistantly spaced in a direction circumferential of the wheel.

To each end portion of the axle or drum 50 1 outwardly of the adjacent wheel 2 is freely engaged, as at 4, an end portion of an elongated lever 5 such lever, when pull is imposed thereupon, being adapted to engage an outstanding projection or finger 3 to effect 55 desired rotation of the axle 1. The axle or drum 1 midway between the applied wheels 2 has disposed radially therethrough an opening 6 through which is adapted to pass a cable or kindred flexible member 7 so that

as the axle or drum 1 is rotated a double winding of the cable or member 7 on the axle or drum 1 will be effected and thus materially increasing the action of the power wheel.

In practice, one end of the cable or member 7 is secured to a suitable anchor while the opposite end is affixed to the element to be lifted or pulled. As the axle or drum 1 is caused to rotate under the action of the levers 5 the resultant winding of the intermediate portion of the cable or member 7 upon the axle or drum 1 will result in the desired pull upon the element.

One of the wheels 2 in close proximity to its periphery has pivotally connected therewith, as at 8, an end portion of an arm 9 of a length to bridge the space between the wheels 2 and which normally has direct contact with a spoke 10 comprised in each of the wheels 2. This arm 9 is normally maintained in such position under the influence of a spring 11 having an intermediate portion coiled about the pivot 8 for the arm 9 and having its extremities coacting with the associated wheel 2 and arm 9 in a well known manner.

As the axle or drum 1 is rotated in one direction, the arm 9 will readily move or swing away from the adjacent spokes 10 to pass the cable or member 7 but just as soon as the arm 9 goes from one side to the other of the cable or member 7 it will automatically return to its normal position and provide means to hold the axle or drum 1 against retrograde or reverse rotation. This 90 is accomplished by contact of the arm 9 with the cable or member 7 as is indicated in Figure 2 of the accompanying drawing.

It will also be understood that when the power wheel is in operation and as the intermediate portion of the cable or member 7 is wound upon the axle or drum 1, the wheel will be free of the ground or other surface, thus facilitating its operation.

In the accompanying drawing I have only 100 illustrated the use of one of the arms 9 but it is to be understood that as many more may be used as the requirements of practice may deem best.

From the foregoing description it is 105 thought to be obvious that a power wheel constructed in accordance with my invention is particularly well adapted for use by reason of the convenience and facility with which it may be assembled and operated, and it will 110

also be obvious that my invention is susceptible of some change and modification without departing from the principles and spirit thereof and for this reason I do not wish to be understood as limiting myself to the precise arrangement and formation of the several parts herein shown in carrying out my invention in practice except as herein-after claimed.

10 I claim:—

1. A device of the class described comprising an axle, spaced wheels fixed thereto, a flexible member having an intermediate portion fixed to the axle between the wheels
- 15 to effect a double winding of the member on the axle when rotated, means for rotating the wheels and axle, an arm pivotally engaged with one of the wheels and normally bridging the space therebetween, and means
- 20 for maintaining the arm in such position.
2. A device of the class described comprising an axle, spaced wheels fixed thereto, a flexible member having an intermediate portion fixed to the axle between the wheels to
- 25 effect a double winding of the member on the axle when rotated, means for rotating

the wheels and axle, and means carried by one of the wheels and engageable with the second wheel for co-action with the flexible member, during a working operation, to hold the 30 wheels and axle against retrograde rotation.

3. A device of the class described comprising an axle, spaced wheels fixed thereto, a flexible member having an intermediate portion fixed to the axle between the wheels to 35 effect a double winding of the member on the axle when rotated, outstanding projections carried by the peripheral portions of the wheels, levers freely engaged with the extremities of the axle and adapted to have 40 contact with the projections, an arm pivotally engaged with one of the wheels and normally bridging the space between the wheels, and means for normally maintaining the arm in such position, the wheels having parts with which the arm contacts when in 45 its normal position to hold the arm against swinging movement in one direction.

In testimony whereof I hereunto affix my signature.

ARTHUR J. LARKIN.
